HEADLIGHT DIFFUSING SHIELD

Rollin H. Williams, Chicago, Ill.

Application August 30, 1950, Serial No. 11,988

Term of patent 7 years

(Cl. D48—32)

To all whom it may concern:

Be it known that I, Rollin H. Williams, a citizen of the United States, residing at Chicago, county of Cook, and State of Illinois, have invented a new, original, and ornamental Design for a Headlight Diffusing Shield, of which the following is a specification, reference being had to the accompanying drawing, forming a part thereof, in which—

Fig. 1 is a side elevational view of a headlight diffusing shield, showing my new design;

Fig. 2 is a top plan view thereof;

Fig. 3 is a cross-sectional view thereof;

Fig. 4 is a bottom plan view thereof;

Fig. 5 is a perspective view thereof.

Fig. 6 is a sectional view taken on line 6—6 of Figure 2 thereof.

I claim:

The ornamental design for a headlight diffusing shield, as shown.

ROLLIN H. WILLIAMS.
